WILLIAM ROSSETTER, OF ACCRINGTON, ENGLAND.

Letters Patent No. 89,692, dated May 4, 1869.

IMPROVEMENT IN LOOMS.

The Schedule referred to in these Letters Patent and making part of the same.

To all whom it may concern:

Be it known that I, WILLIAM ROSSETTER, of Accrington, in the county of Lancaster, England, have invented a new and useful Improvement in Looms; and I do hereby declare that the following is a full, clear, and exact description thereof, which will enable others skilled in the art to make and use the same, reference being had to the accompanying drawings, forming part of this specification.

The object of this invention is to provide an improved arrangement of means for changing self-actingly the shuttle in which the weft is broken, or absent for another shuttle, with the weft ready for weaving, without stopping the loom, as hereinafter fully set forth.

Figure 1, sheet 1, represents a partial front elevation of a loom, provided with my improvements.

Figure 1, sheet 2, represents another partial front elevation.

Figure 2 represents a side elevation, showing the means for supplying a fresh shuttle.

Figure 3 represents a side elevation, showing the means for discharging shuttle when the weft is broken.

Similar letters of reference indicate corresponding parts.

I support the ordinary weft-fork holder *a*, upon an arm, *b*, rising from the transverse shaft *c*, extending across the loom underneath the breast-beam, and carrying at one end a lever, *p*, and at the other a lever, *d*, and arrange the ordinary sector-hammer *a'* in the usual manner for catching the weft-fork when the weft is broken, to oscillate the shaft *C*.

I provide slotted and movable shuttle-guards, *h* and *h'*, at each end of the lay, and support them on yokes *h*, underneath the lay by vertical rods running through the same, the said yokes being provided with arms, *e*, projecting downward and supporting friction-bowls at their lower ends in the same plane of the arms *d* and *p*.

n represents an arm pivoted at *n'*, on a bracket projecting downward from the lay, at the discharging-side of the loom.

The upper end of the said lever is connected to a T-headed slide *n'*, working through the bottom of the rear shuttle-guard of the lay, to eject the shuttle.

O represents a lug on the arm *p*, which is brought into contact with the lower end of the arm *n*, when it is raised by the sector-hammer.

At the end of the breast-beam on the ejection-side, is a plate or table *l* for the reception of the shuttles having spring-guards *l'*, under which the shuttles are received, and projections *l*, which enter corresponding recesses in the shuttle-box when the lay moves up, and form bridges over which the shuttles pass to the said receiving-table.

Similar projections may be also formed on the bottom of the shuttle-box, taking into recesses in the said table.

On the supplying-side of the loom, I arrange on a similar table a shuttle-case *K*, capable of receiving any suitable number of shuttles superposed upon each other, the said case having an opening at the bottom towards the lay, large enough for the bottom shuttle to pass through, and above the said opening spring-guards *m*, to prevent the shuttle from rising up under the action of the forked and bent lever *m'*, pivoted at *m''*, to the frame by which they are thrown upon the lay, bridges being formed at this end similarly to those at the other.

On the pivot *m''*, underneath the lay, I arrange loosely the bent spring-lever *f*, the horizontal part of which passes above the yoke *h*, in a manner to cause the lower end of the said spring-lever to strike the lower end of the lever *m'* when the yoke rises.

When the loom is working, the breakage or absence of the weft is detected, when the shuttle is returning to the weft-fork end, by the said weft-fork, and when the detection takes place, the sector-hammer *a'* catches the hooked end of the weft-fork, and draws the arm *b* back, turning the shaft *c*, and raising the movable shuttle-guards *h* and *h'*.

On the delivery-side of the loom the stud *O* strikes the lower end of the arm *n*, throwing the T-shaped slide *n'* forward, and ejecting the shuttle which is received on the table *l*, under the spring-guards *l'*, where each shuttle is held until the next one follows, driving the first forward under the guards, and so on until a number accumulates to be removed from time to time.

On the replenishing-side, the raising of the yoke *h* by the arm *d*, raises the spring-lever *f*, so that the lower end strikes the lower end of the lever *m'*, throwing the upper end against the bottom shuttle, and forcing it on to the lay. As soon as the shuttle is received into the shuttle-box, the friction-bowl at the end of the projection *e* of the yoke passes into a recess in the arm *d*, which allows the shuttle-guard to fall sufficiently to prevent the shuttle from being thrown back by any shock, especially that of the commencement of the return motion of the lay.

The said friction-bowl dwells in the said recess until the shaft *c* commences its return movement, carrying the arm *d* downward, and allowing the shuttle-guard to fall back. Any suitable springs may be employed for retracting the levers *m'* and *n*.

The ends of the thread of the bobbins in the shuttles on the replenishing-side, may be secured by any suitable means, as the shuttles are placed in the boxes, to cause them to wind off.

My invention is applicable alike to looms having the pickers operated from below or above, and to looms generally.

As it is desirable to prevent the picking-stick on the ejection-end of the lay from making a stroke, until the shuttle has been delivered from the other end, I propose to place on the tappet-shaft a clutch-box, one half on the shaft, and the other half fixed to the pick-

ing-tappet, and the half of the clutch-box on the shaft is shifted at the required time by a lever put in motion by a lever fixed on the rod or shaft *c*.

Having thus described my invention,

I claim as new, and desire to secure by Letters Patent—

1. The slotted and movable shuttle-guards *h* and *h'*, supported on the yokes *h*², and combined with the oscillating arms *d* and *p*, substantially as specified.

2. The combination with the slotted and movable shuttle-guard *h*¹, of the slide *n*², and arm *n*, attached to the lay with the oscillating arm *p*, substantially as specified.

3. The receiving-table *l*, provided with the springs

p, and projections *l*, and combined with the lay having a movable shuttle-guard, substantially as specified.

4. The combination with yoke, *h*¹, supporting the movable shuttle-guard *h*, of the bent spring-arm *f*, lever *m*¹, and shuttle-box, *k*, substantially as specified.

5. The shuttle-box *k*, provided with the spring-guards *m*, substantially as specified.

The above specification of my invention, signed by me, this 21st day of January, 1868.

WILLIAM ROSSETTER.
